UNITED STATES PATENT OFFICE.

GEORGE OTIS DRAPER, OF HOPEDALE, MASSACHUSETTS, ASSIGNOR TO DRAPER COMPANY, OF HOPEDALE, MASSACHUSETTS, A CORPORATION OF MAINE.

RING-SPINNING APPARATUS.

SPECIFICATION forming part of Letters Patent No. 741,777, dated October 20, 1903.

Application filed April 29, 1903. Serial No. 154,755. (No model.)

To all whom it may concern:

Be it known that I, GEORGE OTIS DRAPER, a citizen of the United States, and a resident of Hopedale, county of Worcester, State of Massachusetts, have invented an Improvement in Ring-Spinning Apparatus, of which the following description, in connection with the accompanying drawings, is a specification, like characters on the drawings representing like parts.

This invention relates to high-speed yarn spinning or twisting apparatus of the type wherein the annular traveler support or ring is arranged to rotate when the spindle is in motion at a high rate of speed, the ring at such time being free to yield in any direction under unbalanced strains, the rotation of the ring obviating destructive heating of the traveler by frictional engagement therewith.

At the present time great numbers of rings are in use in the fixed-ring type of spinning and twisting apparatus; and one of the objects of my present invention is the production of means for utilizing a well-known form of ring in apparatus of the revolving type.

Various other novel features of my invention will be fully described in the subjoined specification and particularly pointed out in the following claims.

Figure 1 is a vertical diametrical section on the line 1 1, Fig. 2, of a yarn spinning or twisting apparatus embodying one practical form of my invention, a portion of the ring-rail, spindle, and bobbin being shown in elevation. Fig. 2 is a plan view, partly broken out, of the revolving ring and the co-operating parts, the bobbin and spindle being omitted. Fig. 3 is a view similar to Fig. 1 on the line 3 3, Fig. 4, of a modified form of my invention; and Fig. 4 is a plan view, partly broken out, of the device shown in Fig. 3.

In Figs. 1 and 3 the reciprocating ring-rail R^X , spindle S of any suitable high-speed type and actuated by usual means, (not shown,) and the removable bobbin B , on which the yarn is wound, may be and are all of any usual or well-known construction, the spindle and bobbin extending through a circular aperture 3 in the ring-rail.

Referring to Fig. 1, the ring R is of a well-known pattern in extensive use on the fixed-ring type of spinning and twisting apparatus, the ring having upper and lower flanges r and r' , the traveler t co-operating with the upper flange in the usual manner. I have provided a spring-clamp holder for the ring, said holder in one embodiment of my invention comprising a cylindrical body h , provided with a plurality of longitudinal slits h^X , extending from its upper edge part way toward the bottom of the body. (See Fig. 1.) An external annular groove h' is made in the body near its top, the latter being shown as externally rounded in Fig. 1, and the ring is snapped onto the holder, the inner edge of the flange r' entering the groove h' and being held therein by the spring action of the body. The base of the body is provided with a lateral external flange or lip h^2 , constituting a ball-raceway, and preferably the top face of the flange is upwardly and outwardly beveled, as at h^3 , so that the balls b^X normally rest in the position shown in Fig. 1. Surrounding and concentric with the holder I mount a relatively stationary bearing or confining member c upon the ring-rail, and, as herein shown, said member is attached to the rail by retaining-screws 5. This outer member c has an upturned annular portion c' , which partly overhangs the raceway h^2 , and has a frusto-conical bearing-surface c^X projecting over and at a considerable distance above the series of balls b^X when the ring and its holder are at rest.

By referring to Fig. 1 it will be manifest that the ring and its holder may have a limited radial and vertical movement relative to the member c , the overhanging part c' thereof serving to limit such movements and confine the holder within proper bounds. Until the spindle speed is high enough to cause rotative movement of the ring R the series of balls is at rest; but when the ring is revolving, as in the rotary-ring type of apparatus, the balls are thrown outward by centrifugal force and impinge upon the bearing-surface c^X . A yielding ball-bearing is thus provided, the balls accommodating themselves to the speed of rotation of the holder, so that when-

ever such speed is great enough the balls will roll up the inclined bottom h^3 of the raceway and contact with it and with the bearing-surface c^x .

5 While I have termed the member c , which has the bearing-surface c^x , as a "stationary" member, and have shown it as fixedly secured to the ring-rail, I do not restrict myself to such fixed mode of attachment, as the confining member or shell may be mounted yieldingly on the ring-rail, following the practice in some forms of rotary-ring apparatus.

In the modified form of my invention shown in Figs. 3 and 4 the usual ring R , having upper and lower flanges r and r' , is used, and also the confining or stationary bearing member c , having a frusto-conical bearing-surface c^x , as has been described. A different form of ring-holder is employed, however, 15 and it is shown as a second ring M , practically a duplicate of the ring R , the lower flange r' of the latter being secured to the upper flange m of the ring M in any suitable manner, as by brazing, soldering, &c. The 20 lower flange m' of the holder M supports a split ring p , snapped around the web of the holder and having an upwardly and outwardly beveled face p^x , said split ring constituting a raceway for the series of balls b^x . The 25 lower flange m' of the holder M supports a split ring p , snapped around the web of the holder and having an upwardly and outwardly beveled face p^x , said split ring constituting a raceway for the series of balls b^x . 30 This raceway is thus substantially like the raceway h^2 , heretofore described, and in both of the embodiments of my invention it will be manifest that the series of balls are carried with the revolving ring, and so far as I 35 am aware this feature is broadly new. The base of the holder in either case rests upon the top of the ring-rail when the ring and holder are at rest, as shown in Figs. 1 and 3 of the drawings.

40 From the foregoing description it will be manifest that a well-known form of spinning-ring can be utilized in a revolving-ring type of apparatus with no change in the structure of the ring itself, and this is one of the important features of my invention.

45 My invention is not restricted to the precise construction and arrangement herein shown and described, as the same may be varied or rearranged in different particulars 50 by those skilled in the art without departing from the spirit and scope of my invention.

Having fully described my invention, what I claim as new, and desire to secure by Letters Patent, is—

55 1. The combination with a rotatable ring capable of radial and vertical movement, and having an attached, annular raceway, of a series of balls mounted thereon, and a surrounding, relatively stationary bearing member 60 against which the balls may impinge.

2. The combination with a spinning-ring having upper and lower flanges, and a traveler coöperating with the upper flange, of a 65 rotatable holder capable of radial and vertical movement and attached to the lower flange of the ring, and a bearing for the holder, including a series of balls carried by said holder.

3. The combination with a rotatable ring capable of radial and vertical movement, of a series of balls carried therewith, and a relatively stationary bearing-surface against which the balls are made to impinge by centrifugal force. 70

4. The combination with a rotatable ring, of a bearing therefor including a series of balls 75 and a relatively stationary bearing-surface against which the balls impinge by centrifugal force.

5. The combination with a rotatable ring capable of radial and vertical movement, of 80 a ball-raceway rotatable therewith, a concentric, relatively stationary raceway, and a series of balls interposed between said raceways and vertically supported wholly by the rotatable raceway.

6. The combination of a spinning-ring having upper and lower flanges, a revolute holder with which the ring is connected, a ball-raceway on the holder, a series of balls carried by the raceway, and a concentric and relatively 90 stationary bearing-surface against which the balls are directed by centrifugal force.

7. The combination of a spinning-ring having upper and lower flanges, a revolute holder therefor having an external, annular raceway 95 near its lower end, balls carried by said raceway, and a concentric, relatively stationary bearing-surface against which the balls are directed by centrifugal force.

8. The combination with a rotatable ring 100 capable of radial and vertical movement, of an external annular raceway carried therewith, balls supported by said raceway, and a concentric, relatively stationary bearing-surface overhanging said raceway and with 105 which the balls coöperate when thrown outward by centrifugal force.

9. The combination with a rotatable ring capable of radial and vertical movement, of a yielding bearing therefor including a series 110 of balls bodily rotatable with the ring and controlled by centrifugal force.

10. The combination with a rotatable ring capable of radial and vertical movement, of an external, annular raceway movable therewith and having an upwardly and outwardly beveled bottom, a series of balls carried upon the raceway, and a relatively stationary bearing-surface surrounding the raceway, the 115 balls being directed against said bearing-surface by centrifugal force.

11. The combination of a spinning-ring having upper and lower flanges, a revolute holder for the ring, detachably connected with the lower flange thereof and having an 125 external raceway, a surrounding and relatively stationary bearing-surface, and a series of balls carried by the raceway and adapted to coöperate with the bearing-surface and form a yielding bearing for the ring-holder. 130

12. The combination with a rotatable ring capable of radial and vertical movement, and an external annular raceway movable with the ring, of a series of balls mounted on the

raceway, and a surrounding, relatively stationary confining member having a bearing-surface for the balls overhanging the latter, said member limiting radial and upward movement of the ring and coöperating with the balls when the latter are thrown outward by centrifugal force.

In testimony whereof I have signed my name to this specification in the presence of two subscribing witnesses.

GEORGE OTIS DRAPER.
